UNITED STATES PATENT OFFICE

110,807

DESIGN FOR A SPOON OR ANALOGOUS ARTICLE

Alfred J. Flauder, Trumbull, Conn., assignor to Weidlich Sterling Spoon Co., Bridgeport, Conn., a partnership consisting of Louis Weidlich, Frank B. Weidlich, and William Weidlich

Application November 17, 1937, Serial No. 72,970

Term of patent 7 years

To all whom it may concern:

Be it known that I, Alfred J. Flauder, a citizen of the United States and a resident of Trumbull, in the county of Fairfield and State of Connecticut, have invented a new, original, and ornamental Design for a Spoon or Analogous Article, of which the following is a specification, reference being had to the accompanying drawing, forming a part thereof, and in which—

Fig. 1 is a front elevation of a spoon or analogous article showing my new design;

Fig. 2 is a rear elevation of the same;

Fig. 3 is an enlarged front elevation of the spoon handle;

Fig. 4 shows a cross section of the handle portion of the spoon, taken on line 4—4 of Fig. 3;

Fig. 5 is a further cross section taken on line 5—5 of Fig. 3; and

Fig. 6 is a cross section taken on line 6—6 of Fig. 3.

The dominant feature of the design resides in a spoon handle of the configuration shown, including a central plain panel having an oval end combined with side decorated portions extending down approximately two-thirds of the length of the handle, while the remaining lower portion of the face of the handle is plain except for a rib on each side that extends to the bowl. The back of the handle includes a raised rib extending along the side and around the end, and a central spear-shaped raised rib-like feature formed in the back of the broader portion of the handle as shown in Figures 2 to 6, inclusive.

I claim:

The ornamental design for a spoon or analogous article, substantially as shown and described.

ALFRED J. FLAUDER.
